CLAIM

The ornamental design for a display, as shown and described.

DESCRIPTION

FIG. 1 is a front perspective view of a display showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof; and,

FIG. 9 is another front perspective view of the display of FIGS. 1-8 in another configuration.

The oblique shade lines indicate a transparent portion of the claimed design.

1 Claim, 9 Drawing Sheets
